UNITED STATES PATENT OFFICE.

ALBERT E. POLLOCK, OF CHICAGO, ILLINOIS.

TIRE-GAGE.

1,219,865.

Specification of Letters Patent. Patented Mar. 20, 1917.

Application filed February 19, 1917. Serial No. 149,390.

To all whom it may concern:

Be it known that I, ALBERT E. POLLOCK, a citizen of the United States, residing at Chicago, in the county of Cook and State of Illinois, have invented new and useful Improvements in Tire-Gages, of which the following is a full, clear, concise, and exact description, reference being had to the accompanying drawing forming a part of this specification.

My invention relates to improvements in tire gages and has for its object the production of a device in which the pressure can be quickly and accurately obtained without confusion of figures. A further object is the production of a device in which the reading is obtained without the aid of a spring-controlled gage bar.

These and such other objects as may be hereinafter set forth are attained by my device, embodiments of which are described in the following specification and fully set forth in the accompanying drawing, in which—

25 Figure 1 represents a front elevation of my device;

Fig. 2 represents a rear elevation of my device;

Fig. 3 represents a sectional view of my 30 device;

Fig. 4 represents a perspective view of the indicator tube;

Fig. 5 represents a sectional view of the upper end of Fig. 4;

35 Fig. 6 represents a sectional view of the piston head;

Fig. 7 represents a perspective view of the valve opener;

Fig. 8 represents a sectional view of the 40 top of a modified form;

Fig. 9 represents a sectional view showing a modified form of spring; and

Fig. 10 represents a sectional view showing a modified form of Fig. 5.

45 Like numerals of reference indicate like parts in the several figures of the drawing.

Referring now to the drawings, 11 represents the main barrel or shell of the gage having an opening 12 exposing a number 50 13. An open cap 14 is provided at the bottom and a closed cap 15 at the top which may or may not be screw-threaded, as desired. A slot 16 is formed in the upper half of the rear of the shell to permit the movement of the releasing handle 17 when the device is in use.

An upper spring containing tube 18 is mounted within the barrel, over the top of which is secured the cap 15 and within which is mounted the spring 19 extending 60 from the upper cap to the bottom of the device and surrounding the piston rod 20 which at its bottom is secured to the piston head 21 in the manner shown in Fig. 6. Within the lower half of the barrel is mounted 65 the indicating tube 22 resting at the bottom on the top of the piston head at 23, so that the upward movement of the piston head carries the indicator tube with it.

The indicator tube 22 is provided with 70 a recess portion 24 extending lengthwise of the tube on which is placed indicating numbers 13. The upper portion of the tube is slotted at its rear forming a tongue 25 that is sprung outwardly and carrying at the top 75 the releasing handle or button 17. This spring so formed is of sufficient strength to normally hold the indicating tube in any position to which it may be forced by the upward movement of the piston. The valve 80 opener 26 fits tightly within the main barrel at its bottom and rests on the inturned flange 27 of the open cap 14.

In Fig. 7 the opener is shown inverted and the valve-releasing stem 28 has an opening 29 communicating with the slot 30 in the side wall.

A rubber ring or washer 31 surrounds the stem 28 forming a cushion.

In the modification illustrated in Fig. 8, 90 I provide a central tube 32 fitting within the spring 19 and serving for a guide for the piston rod 20 in its upward movement.

In Fig. 9 I have shown a spring 33 formed circumferentially of the barrel and integral 95 therewith.

In Fig. 10 I have shown the indicator barrel provided with a boss 34 to protect the indicator numbers from wear.

When the parts are assembled as shown 100 in Fig. 3, the various parts fit snugly together. The open end of the gage is pressed on the top of the rim valve when it is desired to ascertain the pressure within the tire. The member 28 unseats the valve and 105 the air rushes into the openings 29 and 30 in the valve opening 26 and under the piston head 21, forcing it up against the pressure of the spring 19 carrying the indicator barrel 22. The barrel rises until the pressure 110 in the tire and gage are equal and a number 13 appearing through the window or

opening 12 shows just what that pressure is. Only a single number appears, so there is no confusion or uncertainty as to the pressure.

When the gage is removed, the piston 5 drops back, forced by the spring, but the indicator tube remains at its highest position, held there by the spring 25 and the pressure can be read without discomfort.

To bring the indicator tube back into normal position, the button 17 is pressed inwardly, thus releasing the pressure of the spring and the barrel is slid down by pressing downwardly on the button. It is not essential to have the button on the spring 15 member, but it makes a much better construction.

In my device, the pressure can be read at any time without stooping into an uncomfortable position and the indicator shows the pressure until the indicator tube is manually slid back.

By turning in the lip 27, I make it impossible to force out the piston head or washer, no matter how hard the pressure 25 is applied.

By the use of the open window with a single number exposed, I protect the indicator from wear and increase its accuracy. The opening is preferably large enough so 30 that a number may always be read. Modifications are, of course, possible that still come within the scope of my invention.

I claim:

1. A tire gage comprising an outer tubular shell, a cap fitting over the top thereof, a piston head fitted within said shell and provided with a piston rod, a coiled spring surrounding the rod and bearing at one end on the cap and at the other end on the piston, an indicator member loosely seated on the piston head and slideable within said shell, said member bearing a pressure indicating scale, means below said piston head

adapted to establish communication between the interior of the shell and the interior of a pneumatic tire and including tire valve unseating means, a portion of said indicator member being sprung outwardly and adapted to bear against the interior of said shell to hold said member in indicating position after said gage is removed from the tire valve, there being a small opening through said shell so positioned that the indicated pressure may be read, and means for returning said indicating member at will. 55

2. A tire gage comprising an outer tubular shell having a slot extending longitudinally at its upper portion, a cap fitting over the top thereof, a piston head fitted within said shell and provided with a piston rod, a coiled spring surrounding the rod and bearing at one end on the cap and at the other end on the piston, an indicator member loosely seated on the piston head and slideable within said shell, said member bearing 60 a pressure indicating scale, means below said piston head adapted to establish communication between the interior of the shell and the interior of a pneumatic tire and including tire valve unseating means, a portion of said indicator member being sprung outwardly and adapted to bear against the interior of said shell to hold said member in indicating position after said gage is removed from the tire valve, there being a small 65 opening through said shell so positioned that the indicated pressure may be read, and a handle mounted on said outwardly sprung portion and projecting through said slot whereby said indicating member can be 70 manually returned to its non-registering position after a reading. 75

In witness whereof, I have hereunto subscribed my name.

A. E. POLLOCK.
